UNITED STATES PATENT OFFICE.

FREDERICK E. FARNUM, OF BOSTON, MASSACHUSETTS.

COLLAPSIBLE TUBE CONTAINER.

Application filed July 7, 1925. Serial No. 41,904.

To all whom it may concern:

Be it known that I, FREDERICK E. FARNUM, a citizen of the United States, and resident of Boston, in the county of Suffolk, State of Massachusetts, have invented certain new and useful Improvements in Collapsible Tube Containers, of which the following is a specification.

This invention relates to collapsible tube containers for paste and like substances and is intended to provide a simple, inexpensive and durable device for sealing the tube and expelling the contents so constructed that it does not interfere with packing the tubes in the usual cartons.

It has been the practice heretofore to seal the tubes with an elongated sealing strip folded along a medial line and clamped over the flattened end of the tube, the contents being expelled by compressing the body of the tube. It has been proposed to provide means for rolling up the tube from its sealed end using the sealing strip as the axis of such movement and providing it either with a separate slotted key or with an outwardly projecting extension that is an integral part of the strip. In either case, however, the projecting finger grip or handle interferes with inserting the tube in its carton which is usually made as small as will permit the insertion of the tube.

The present improvement provides the sealing strip with a pivotally connected finger grip or handle thereby permitting the handle to be folded up against the side of the tube when inserted in the carton while allowing it to swing outwardly in convenient and effective position to function on a twisting handle when the container is removed from the carton for use.

This and other features of the invention will be described in the following specification and will be defined in the claims hereto annexed.

In the accompanying drawings, I have illustrated a simple and convenient embodiment of my invention, in which

Fig. 1 is a side elevation of a complete container showing the expelling handle in extended position for use.

Fig. 2 is a similar view showing the handle in its folded or idle position for packing in the carton.

Fig. 3 shows a cross-section through the sealed end of the tube.

Fig. 4 is a detail showing the form of the

sealing strip before it is folded and applied to the tube.

Fig. 5 is an enlarged cross-section through the sealed end of the tube showing the strip and the handle in assembled position on the tube, taken at right angles to the sectional view of Fig. 3.

Following the usual practice the tube forming the body of the container is provided at its delivery end with a screw cap or closure 2, and at its filling and sealing end is flattened to bring the opposing end edges 1^a into close contact.

The sealing member 3 comprises an elongated strip of thin folded sheet metal the length of whose body substantially corresponds to the length of the flattened edge portion 1^a of the tube so that it may be folded around and clamped upon the exterior surfaces of the end edge portion by doubling along its medial line into a V-shaped cross-section. The strip may be provided with the usual indent 5 to force the subtending soft material into the opposed slots 4 to form an interlocked engagement for effectively sealing the end of the tube.

In the present form of the improvement the sealing strip or member is formed with an integral tongue or extension 6 projecting from one end for about half the width of the strip and this tongue forms the means for attaching a twisting handle 7 which may be made of any suitable form or material to permit the insertion of the tongue 6 through an interior opening so that the tongue when inserted may be doubled back on itself to loop around the adjacent portion of the handle.

As shown the handle or finger grip 7 is preferably in the form of a wire loop dimensioned so that in extended position it forms a strong and convenient grip or handle that facilitates twisting the sealing strip to gradually roll the flattened portion of the tube on it as an axis to expel the contents of the container by compression so produced.

It will be noticed by reference to Fig. 5 that the tongue 6 when folded back around the wire 7 is carried inside so as to be pinched or clamped between the two folds or wings of the body of the clamping and sealing strip and that its looped portion forms a bearing in which the wire loop 7 is free to swing either to extended position for service as shown in Figs. 1 and 5

or to infolded position as shown in Fig. 2.

It matters not how often the twisting handle or loop is moved back and forth from idle to extended position since such movement involves no flexing of the metal which would speedily result in breaking off a twisting member that is integral with the sealing strip. Consequently the handle will continue to function perfectly until the tube is emptied of its contents. After the rolling up of the end of the tube has begun the handle 7 swings only through a quarter turn or a little more but as this position is in the plane of the thickness of the tube there is ample room for it in the carton when in such position.

What I claim is:

1. A collapsible container for paste or the like embracing in its construction a tubular body of flexible sheet material having a discharge orifice at one end and having its opposite end edges clamped between a sealing strip, said strip comprising an elongated blank of thin sheet metal folded along a medial line to embrace the end edge portion of the tube and being provided at one end with a pivotally attached handle arranged to swing from infolded position against the clamping strip to extended position to serve as a handle.

2. A combined sealing and expelling device for a collapsible tube comprising an elongated strip of thin metal adapted to be folded along a medial line to cover and clamp the flattened end edges of the tube, and a gripping loop forming a handle pivotally attached to an endwise extension of said strip so as to swing inward against the clamping strip and outward beyond the tube, to facilitate expulsion of the contents by twisting the handle.

3. A combined sealing and expelling device for a collapsible tube comprising an elongated strip dimensioned to be folded over and cover the flattened end portion of the tube, and having an endwise extension, a handle formed with an interior opening dimensioned to permit said extension of the strip to be passed through and double back on itself whereby the handle is pivotally attached to the sealing strip to be swung inward to position for packing or outward to form a member for rolling the end of the tube about the sealing strip to expel the contents.

4. A combined sealing and expelling device for a collapsible tube embracing an elongated strip of thin metal doubled upon itself along a medial line to tightly embrace and seal the flattened end of the tube, a wire loop, a tongue extending from one end of the strip through said wire loop and folded back to lie between the doubled portion of the strip, whereby the loop is pivotally secured to the strip so that it may be folded back thereon or form an extension convenient to be grasped and twisted to expel the content of the tube.

In witness whereof, I have subscribed the above specification.

FREDERICK E. FARNUM.
